(57) **CLAIM**

The ornamental design for a basket for a boat rail, as shown and described.

DESCRIPTION

FIG. 1 is a front view of a basket for a boat rail; FIG. 2 is a right side view thereof the left side view being a mirror image;

FIG. 3 is a top view thereof;

FIG. 4 is a bottom view thereof;

FIG. 5 is a back view thereof; and,

FIG. 6 is an isometric view thereof.

The broken lines in FIGS. 5 and 6 showing the three wires on the basket depict the portions of the basket for a boat rail that form no part of the claimed design, while all other broken lines in FIGS. 1-6 showing the boat rail segment depict unclaimed environment only and form no part of the claim.
